Primary Examiner — Darlington Ly*Assistant Examiner* — Nasim Abdulaziz Ali(57) **CLAIM**

The ornamental design for a bicycle pedal, as shown and described.

DESCRIPTION

FIG. 1 is a front-right-top perspective view of the bicycle pedal showing my new design;

FIG. 2 is a front elevational view thereof;

FIG. 3 is a rear front elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view from another angle of view thereof.

The broken lines in the drawings illustrate portions of the bicycle pedal which form no part of the claimed design.

1 Claim, 8 Drawing Sheets(56)
